Primary Examiner — Elizabeth J Oswecki(74) *Attorney, Agent, or Firm* — Chainey P. Singleton; Chalker Flores, LLP(57) **CLAIM**

The ornamental design for a removable stick on golf cleats for footwear, as shown and described.

DESCRIPTION

FIG. 1 is an isometric view of a removable stick on golf cleats for footwear showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.
